UNITED STATES PATENT OFFICE.

PERCIVAL S. TICE, OF DETROIT, MICHIGAN.

CARBURETER.

1,300,517.

Specification of Letters Patent. Patented Apr. 15, 1919.

Application filed June 27, 1917. Serial No. 177,176.

To all whom it may concern:

Be it known that I, PERCIVAL S. TICE, a citizen of the United States, residing at Detroit, in the county of Wayne and State of Michigan, have invented new and useful Improvements in Carbureters, of which the following is a specification, reference being had to the accompanying drawings, forming a part thereof.

10 The purpose of this invention is to provide an improved construction of a carbureter adapted to yield more uniform and complete admixture of the air and liquid fuel. It consists in the elements and features of construction shown and described, as indicated in the claims.

In the drawings:

Figure 1 is a vertical section axial with respect to the passages of a carbureter embodying this invention.

Fig. 2 is a section at the line, 2—2, on Fig. 1.

Fig. 3 is a section at the line, 3—3, on Fig. 1.

25 The carbureter illustrated in the drawings is shown as having conventional means, commonly called the float chamber, for maintaining approximately uniform level of liquid for supplying the mixing chamber.

30 Such float chamber is shown at 1, having communication from the top through the passage, 2, with the main air inlet passage, 3, of the carbureter, (controlled at its inlet by a throttle valve, 4, of any desired type),

35 and having communication from the lower part through a restricted or metering orifice, 5, formed in the metering plug, 6, with the liquid fuel inlet passage, 7, formed in what may be termed the nozzle member, 8. Said

40 nozzle member comprises an axially-aper-tured boss, 8^a, projecting interiorly and exteriorly of the main air inlet passage, 3, and the terminal member, 9, screwed into the upper end of said boss, 8^a, and projecting

45 up into the main mixing chamber, 20. This mixing chamber is formed by means of a sleeve, 10, which depends from the wall of the narrowed upper portion, 11, of the passage leading to the engine intake, concen-

50 trically within the lower enlarged portion thereof, forming an annular pocket, 3^a, which is a continuation of the air inlet passage 3 above the lower end of said depending sleeve

55 10. 12 is a tubular member constituting an air jet inlet, hereinafter referred to as the air jet member. It is screwed into the lower

end of the boss, 8^a, and rendered leak-tight at its junction therewith by a gland, 15. At the portion which extends above the thread and above the port, 16, of communication of 60 the float chamber with the fuel inlet passage, 7, its exterior diameter is less than that of said fuel inlet passage so that an annular space is defined between it and the wall of said fuel inlet passage, thus making said 65 fuel inlet passage annular. Near the upper end of the air jet member, 12, it is sharply constricted as shown at 17, the constriction extending for a short distance and the axial cavity of the air jet member being enlarged 70 immediately beyond the constriction, forms an initial mixing chamber, 18, for the air and fuel, the mixing being effected by means of lateral slits, 19, 19, forming apertures leading from the air jet to the encompassing 75 portion of the liquid fuel inlet passage below the upper end of the latter. The air jet drawn in through the air jet member, 12, having its velocity greatly increased and its passage through the constriction, 17, and 80 expanding rapidly at its emergence beyond that constriction into the mixing chamber, 20, causes a relatively high vacuum to be produced immediately above the constriction,—that is, at the level of the slits, so that 85 the liquid fuel which is lifted in the fuel inlet passage as hereinafter more fully explained, to the margin of said slits is sucked over the margin through the slits transversely to the movement of the air jet and 90 thoroughly broken up thereby in said initial mixing chamber into which air from the main mixing chamber 20 is also drawn by the entrainment of said high velocity jet which emerges from the constriction 17. 95 From this initial mixing chamber 18 the mixture emerges into the main mixing chamber 20 formed by the sleeve, 10, for further admixture with the larger quantity of air entering through the main air inlet. The 100 operation of the structure described, may be more fully stated as follows:

The well understood operation of the float in the float chamber, 1, maintains the liquid fuel at substantially the level of the lower 105 end of the sleeve, 10, forming the main mixing chamber, as indicated by the dotted line, x—x, and this is the condition when the engine is at rest. Upon starting the engine, the partial vacuum produced by the intake 110 stroke of the engine in the intake passage operating to produce a higher degree of

vacuum in the main mixing chamber, 20, than in the float chamber causes the liquid fuel in the annular liquid passage, 7, to rise, and the structure is designed to have 5 the air jet member, 12, adjusted in the nozzle so as to position the slits, 19, 19, at the level to which the liquid fuel will be raised in the annular fuel inlet passage, 7, under conditions of minimum engine suction, the 10 liquid tending to rise above the level of said slits in case of higher suction. The same engine suction while taking in the main supply of air through the main air inlet, 3, causes an inrush through the air jet member, 12, of an air jet whose velocity is relatively high at its emergence from the constriction, 17, in the air jet passage, so that the higher degree of vacuum produced at that 15 point draws the liquid fuel through the slits and atomizes it in the initial mixing chamber, 18, as hereinabove stated.

The efficiency of the device for the purpose of producing a proper mixture at all times is largely dependent upon the metering 20 of the communication from the float chamber to the liquid inlet passage, 7, that is, the restriction of that communication to a diameter such with relation to the cross-sectional area of the annular fluid inlet passage that the variation in vacuum to which 25 the liquid in that passage is exposed, in comparison with the vacuum operating on the liquid in the float chamber, shall not hasten the flow of the liquid from the float chamber 30 more than proportionately to the flow of air through the main air inlet passage.

I claim:—

1. In a carbureter, in combination with a main air inlet passage, an air jet discharging 40 in the main air inlet passage, a fuel inlet passage extending adjacent to the air jet passage, the air jet passage being constricted at a short distance back of its discharge in the main air inlet passage, and laterally apertured immediately beyond the restriction for communication with the fuel inlet passage, said fuel inlet passage being extended a short distance beyond said apertures and open at the end therebeyond for 45 communication with the main air inlet passage.

2. In a carbureter characterized as set out

in claim 1, the fuel inlet passage being an annular passage encompassing the air jet passage.

3. In a carbureter characterized as set out in claim 1, the air jet passage being enlarged beyond the construction thereof, forming a minor mixing chamber within the mixing chamber which is formed by the main air 55 inlet passage.

4. In a carbureter characterized as set out in claim 1, the lateral apertures of the air jet being dimensioned for admitting fuel from the fuel passage in thin relatively wide-spread jets or spray.

5. In a carbureter characterized as set out in claim 1 foregoing, the air jet passage being enlarged beyond the constriction thereof, forming a minor mixing chamber within the mixing chamber which is formed by the main air inlet passage, said minor mixing chamber being of a less cross-sectional area than the portion of the main mixing chamber which encompasses the air jet and fuel 70 inlet passage at the plane of discharge therefrom.

6. In a carbureter, in combination with a mixing chamber, a liquid level governing chamber adjacent thereto, having a suction 80 connection from above the liquid level of said governing chamber leading to the mixing chamber, a liquid fuel passage from the lower part of the governing chamber into the mixing chamber, and a metering device 85 in said passage for restricting the flow of liquid therethrough, a main air inlet passage into the mixing chamber, an air jet discharging in said main air inlet passage, the fuel passage from the level-governing 90 chamber being adjacent to said air jet passage; the air jet passage being constricted a short distance back of its discharge in the main air inlet passage, and laterally apertured beyond the restriction for communication 95 with said fuel passage, the latter being extended a short distance beyond said apertures and open at the end therebeyond for communication with the main air inlet passage.

In testimony whereof, I have hereunto set my hand at Chicago, Illinois, this 21st day of June, 1917.

PERCIVAL S. TICE.
